UNITED STATES PATENT OFFICE.

WILLIAM B. FRANKLIN, OF HARTFORD, CONNECTICUT, ASSIGNOR TO COLT'S PATENT FIRE-ARMS MANUFACTURING COMPANY, OF SAME PLACE.

IMPROVEMENT IN CARTRIDGE FEED-CASES FOR MACHINE-GUNS.

Specification forming part of Letters Patent No. **159,404**, dated February 2, 1875; application filed September 16, 1874.

To all whom it may concern:

Be it known that I, WILLIAM B. FRANKLIN, of Hartford, in the county of Hartford and State of Connecticut, have invented a new Improvement in Cartridge Feed-Case for Machine-Guns; and do hereby declare the following, when taken in connection with the accompanying drawings, and the letters of reference marked thereon, to be a full, clear, and exact description of the same, and which said drawings constitute part of this specification, and represent, in—

Figure 1 perspective view, and in Fig. 2 vertical central section.

This invention relates to an improvement in the cases in machine-guns for the purpose of introducing the charged cartridge with special reference to the Gatling gun, and as an improvement on the feed-case shown in a patent granted to Gatling, February 28th, 1871, No. 112,138.

The feed case is a tube of nearly rectangular cross-section, in which the cartridges are placed, one upon another, with their axes nearly parallel. Such a filled case is applied in a nearly vertical position to the hopper of the gun, and the cartridges fall from the case into the hopper, as required to supply the gun. The case in the said Gatling patent is constructed with a flap hinged to one edge of the lower end of the feed-case, and held closed by a spring-latch upon the other side. This flap is an inconvenience in the use of the case, is liable to get out of repair, and adds materially to the cost of the feed-cases. The object of this invention is to avoid entirely the use of the flap; and it consists in combining with the case a spring, the nose of which extends across the lower or open end of the case to directly support the cartridges in the case, as more fully hereinafter described.

A is the feed-case of substantially the usual form and construction, with a slit, B, in one side; D, a weighted follower moving freely up and down within the case and lies upon the cartridges C, and should be of sufficient weight to overcome any resistance tending to prevent the free falling of the cartridges from the case when in place upon the gun; F, a thumb-piece attached to the follower through the slit B for the purpose of moving the follower by hand when occasion requires. Upon the side of the case is a spring, G, terminating at the lower end in a head, H, which extends across the open end or mouth of the case, as seen in Fig. 2, sufficiently far that the lower cartridge will rest directly upon it, and thereby support the column of cartridges above. The head should extend at least to the center line of the cartridges, in order that the weight of the column may not tend to force back the head and allow the cartridges to prematurely escape.

In charging the case the head is withdrawn, as in broken lines, Fig. 2, the spring G readily allowing such movement, and it is also drawn back in like manner, when the case is placed in the gun to allow the cartridges to fall from the case into the hopper, as they are required. By this construction the hinged flap usually employed is dispensed with.

I claim—

In combination with the feed-case A of a machine-gun the spring G and head H, extending over the mouth or open end of the case, substantially as described, and for the purpose of supporting the cartridges directly thereon.

W. B. FRANKLIN.
